METHOD OF AND BLANK FOR MAKING
CHANNELED BAG FRAMESWilliam C. Hiering, Newark, N. J., assignor to
The J. E. Mergott Company, Newark, N. J., a
corporation of Delaware

Application July 1, 1936, Serial No. 88,346.

4 Claims. (Cl. 113—116)

This invention relates to frames for hand bags, and more particularly to a method of making said frames.

Hand bag frames are generally U-shaped, and in order to prevent buckling and distortion at the corners, heretofore, considerable care has been necessary in the bending of the frame.

In U. S. Patent No. 1,925,804 granted to me on September 5, 1933, there is described a method of making a frame whereby neat, sharp and solid corners are produced which are free from open joints, with no puckering of the metal. That patent applies especially to a channeled frame member opening upwardly.

15 It is an object of the present invention to provide a method of making a hand bag frame which is substantially tubular, having a lateral opening. In accordance with the invention, a blank is provided from which the frame is formed. 20 This blank has cut therein triangular openings and trapezoidal notches in the edge of the blank adjacent the triangular openings. From this blank there is formed a substantially tubular member which is bent into a U-shaped frame member, the openings and notches enabling the tubular member to be bent without puckering or unsightly joints.

25 Heretofore, it has been the general practice to make frames of the type herein considered by riveting or spot welding pieces of metal together, or by bending metal and then riveting or spot welding additional pieces at the corners to reinforce sections of the frame at the corners or angles thereof. Obviously, such structures and 30 methods are expensive.

35 It is, therefore, a further object of my invention to provide a method for making a tubular hand bag frame from a single sheet of bendable metal, without resorting to spot welding or riveting or the attaching of an additional piece of metal to the frame member at the corners thereof.

A further object is the provision of a novel 40 blank for forming a tubular frame member, which blank consists of a single strip of material provided with openings and notches therein to enable it to be bent to provide neat angled corners.

45 These and other advantageous objects, which will later appear, are accomplished by the simple and practical construction and arrangement of parts hereinafter described and exhibited in the accompanying drawing, forming part hereof, and in which:

50 Fig. 1 is a perspective view of a frame member embodying my invention,

Fig. 2 is a perspective view of a blank from which the frame member is formed,

Fig. 3 is a plan view of a portion of the tubular member, showing a step in the formation of the frame member,

5 Figs. 4 and 5 show further steps in the forming of a corner of a U-shaped frame member,

Fig. 6 shows a corner of a frame member formed in accordance with my invention, and

Fig. 7 is a view showing the obverse side of the 10 corner shown in Fig. 6.

Referring to the drawing, in Fig. 2 there is shown a metal strip 8 from which the frame members are formed. The strip is provided with triangular openings 9, and adjacent each opening 15 9 the edge of the strip is provided with trapezoidal notches 10, thus forming connecting strip 11 between the openings 9 and the notches 10. After providing the strip 8 with the openings 9 and notches 10, the strip is then bent into a substantially tubular shape as indicated in Fig. 3, having the edges 12 and 13 spaced from each other on the same side of the tubular member. The tubular member is then bent into a U-shape, each corner being formed as shown in Figs. 4 and 5, 20 25 the connecting strip 11 being doubled back upon itself as indicated in Fig. 5 and the corners thus produced have the appearance shown in Fig. 6.

By means of this method, I am able to produce 30 neat right-angled corners in a substantially tubular U-shaped hand bag frame member, without cracking or buckling of the metal at the corners during the bending process.

The foregoing disclosure is to be regarded as 35 descriptive and illustrative only, and not as restrictive or limitative of the invention, of which obviously an embodiment may be constructed including many modifications, without departing from the general scope herein indicated and denoted in the appended claims.

Having thus described my invention, what I 40 claim as new and desire to secure by Letters Patent, is:

1. The method of making a substantially tubular bag frame member having an angled corner 45 from a flat metal strip, comprising providing the strip with a triangular opening and a trapezoidal notch in the edge of the strip adjacent said opening forming a connecting strip between the opening and the notch, then bending the strip into a 50 substantially tubular shape so that the connecting strip forms a part of a wall of the member, then bending the tubular member so that the connecting strip will be doubled back upon itself to produce a right angled corner.

2. A blank for making a hand bag frame member, comprising a strip of bendable sheet material having spaced trapezoidal notches in one longitudinal edge thereof and triangular openings in alignment with and spaced from each notch, transversely of said strip, the bases of said openings and notches being adjacent each other.
3. A blank for making a substantially tubular U-shaped frame member, comprising a strip of bendable sheet material having a trapezoidal notch in the longitudinal edge of said strip, said strip having a triangular opening therein adjacent said notch providing a connecting strip between the opening and the notch, the bases of

said opening and notch being adjacent each other.

4. The method of making a cylindrical tubular U-shaped bag frame member having right angular corners, comprising forming trapezoidal notches in the longitudinal edge of a strip of bendable sheet material, forming a triangular opening in said strip adjacent each notch to provide a connecting strip, bending the strip into a substantially cylindrical tubular shape, and then bending the tubular shaped strip so that the connecting strips will be bent back upon themselves and the triangular openings will be closed to provide angled corners.

WILLIAM C. HIERING.
